PALLET NET SECUREMENT SYSTEM**CROSS-REFERENCE TO RELATED APPLICATIONS**

This application claims the benefit of U.S. Application No. 63/186,635, filed on May 10, 2021, by the present inventor, entitled "Pallet Net Securement System", which is hereby incorporated by reference in its entirety for all allowable purposes, including the incorporation and preservation of any and all rights to the patentable subject matter of the inventor, such as features, elements, processes and process steps, and improvements that may supplement or relate to the subject matter described herein.

STATEMENT REGARDING FEDERALLY SPONSORED RESEARCH OR DEVELOPMENT

Not Applicable

BACKGROUND OF THE INVENTION

This invention generally relates load securement systems and more specifically it relates to flexible securement and tensioning members encased in protective coverings.

Various cargo securement configurations are known in the field of art, including the use of flexible webbed straps and elastic members. U.S. Pat. No. 2,455,237, filed on Oct. 29, 1946, by Frank Davis, and issued on Nov. 30, 1948, teaches a cargo tie-down blanket comprised of webbed straps attached to a fabric sheet, with hooked "take-ups" on the straps to secure the blanket to a load-carrying pallet. The fabric is shaped with sides to fold down to cover the sides of the cargo, and with a plurality of loops along the length of the webbing to offer additional or alternate securement points for the blanket. U.S. Pat. No. 5,050,924, filed on Jan. 30, 1991, by George Hansen, and issued on Sep. 24, 1991, teaches an expandable tarpaulin assembly comprising a sheet of material with a perimeter and X-pattern array of elasticized tie-down cords routed within protective sleeves, with intermittent gaps in the protective sleeves to permit access to the elasticized cords for attachment to anchor points, and the cords terminating in a hook on each end. U.S. Pat. No. 4,979,776, filed on Jul. 29, 1990, by David Schweickert, filed on Jan. 29, 1990, and issued on Dec. 25, 1990, and U.S. Pat. No. 6,244,139, filed on Jun. 7, 1999, by David Weyand, and issued on May 1, 2001, teach variations of a tarpaulin cover with an elastic band extending around a portion of the perimeter within a hem, where the hem has openings to access the elastic cord for securement to the cargo container. Each of these inventions was found to have utility in their novel and nonobvious designs. Each of these patents is hereby incorporated by reference in its entirety to provide examples of the state of the art and background of the current invention, challenges perceived by those in the field of art, objectives in creating a more desirable design, and to provide examples of standard terms and nomenclature employed in the field of art.

It would be an improvement to the field of art to provide a cargo securement system wherein cargo straps possess anchor points for accepting connection to attachable and replaceable tensioning cords and openable protective sleeves in which the anchor point and tensioning cord may be housed for the protection of the tensioning cord and of users who could be injured by the failure or uncontrolled release of a tensioning cord. It would also be an improvement to the field of art to size the dimensions of the spacing

of the cargo straps and tensioning points to accommodate a combination of coordinately sized containers for rapid and safe securement to a cargo pallet.

Other objects and advantages of the present invention may become obvious to the reader and it is intended that these objects and advantages are within the scope of the present invention. To the accomplishment of the above and related objects, this invention may be embodied in the form illustrated in the accompanying drawings. Attention being called to the fact, however, that the drawings are illustrative only, and that changes may be made in the specific construction illustrated and described within the scope of this application.

15 BRIEF DESCRIPTION OF THE DRAWINGS

The invention will be explained in conjunction with an illustrative embodiment shown in the accompanying drawings, in which:

20 FIG. 1 is a perspective view of a loaded cargo pallet secured by an exemplary embodiment of the present device.

FIG. 2 is a schematic normal view of an exemplary embodiment of the present device.

FIG. 3 is a schematic depiction of a portion of a strap shown in FIG. 1 without a cord cover.

FIG. 4 is a schematic depiction of a portion of a strap shown in FIG. 1 with a cord cover partially folded back.

FIG. 5 is a detailed side view of a portion of a strap shown in FIG. 3, and cut at line A-A.

30 FIG. 6 is a schematic normal view of an alternate exemplary embodiment of the present device.

FIG. 7 is a schematic depiction of a top view of a prior art loaded pallet suitable for use with the current device.

FIG. 8 is a schematic depiction of a side view of a prior 35 art loaded pallet suitable for use with the current device.

FIGS. 9-11 are schematic depictions of the side view of prior art bins arranged on a pallet suitable for use with the current device.

FIG. 12 is a perspective depiction of a prior art loaded 40 pallet with bins secured by a prior art securement wrap.

FIG. 13 is a perspective view of an exemplary embodiment of the present device.

FIG. 14 is a partial view of a strap end of the device shown in FIG. 13.

45 FIG. 15 is a partial view of details of the strap end shown in FIG. 14.

FIG. 16 is a supplemental partial view of details of the strap end shown in FIG. 14.

50 DESCRIPTION OF THE ILLUSTRATED EMBODIMENT

In this description relative terms may be used, such as "generally" and "about". Additionally, measurements are 55 provided, some of which are qualified with a relative term, and others that are not. All measurements provided may include some variations. It is the inventor's intent to point out here and periodically use these words to express that there may be variations to a physical measurement or size being described, but that one of ordinary skill in the art would appreciate the degree of variation that may be present while effectively still within the description of the particular physical relationship.

In this description dimensional and relational terms may 60 be used, such as "length", "width", "longitudinal", and "transverse". Such terms are given their general normal meaning and are used consistently throughout this disclosure

to denote the relative relational positioning of elements of the described device and in identifying different similar elements.

Turning now descriptively to the drawings, FIG. 1 shows an exemplary embodiment of a securing system 10 configured for use with a loaded pallet 3. The exemplary securing system 10 is shown to secure individual containers (also called bins) 2 on a pallet 1 for transfer as an integral unit. The securing system 10 may be suitable for use with traditional pallets, primarily comprised of wood, as well as alternate pallets, comprised of various materials, including polymers and composites. It is understood by those of ordinary skill in the art that pallets 1 may have attachment points for securing devices, and if they do not inherently, suitable attachment points on a pallet 1 may be easily configured.

The current net securing system 10 may be found to be appropriate for use with other systems besides pallets. The current net securing system 10 may be suitable for use to secure cargo within a transport, such as a truck or trailer. Alternatively, the current net securing system 10 may be suitable for use to secure a barrier, such as a pool cover or temporary walling system. The limitations of the current system are only defined by the formal claims, and the novelty and non-obviousness nature of the system.

Referring now primarily to FIGS. 2 through 5, an exemplary securing system 10 is shown to comprise at least one strap 12, and in some configurations, a plurality of straps 12. In an exemplary embodiment, a strap 12 may have an adaptable end 16. In an exemplary embodiment, an adaptable end 16 may have an anchor point 14. In the exemplary embodiment, a strap 12 may be understood to be a flexible cargo strap, known in the field of art. Additionally, a strap 12 may have a cinching mechanism 36 that would permit adjustment of the length of a portion of strap 12. Cinching mechanisms 36 are known in the field of art, and may include a cam buckle tie-down, a suitable example of which may be available from the Uline Corporation, in Pleasant Prairie, Wisconsin.

Referring now, additionally, to FIGS. 13 through 16, in an exemplary embodiment, an adaptable end 16 may include at least one hook 20 secured to an end of a tension cord 18. In the exemplary embodiment, an adaptable end 16 is shown to have a hook 20 on each end of tension cord 18. One hook 20 may engage anchor point 14 on strap 12, while the other hook 20 is a working hook that may remain free to engage the pallet 1 during use. It is appreciated that an adaptable end may have alternative arrangements for securing a hook 20 to the strap, which may include a tension cord 18. It is appreciated that an adaptable end may have a tension cord 18 secured to the strap 12 in an alternate manner than with the shown anchor point 14. This working hook 20 may be referred to as a net anchor, either separately or in conjunction with other components that facilitate attachment of the net, such as the tension cord 18.

In an exemplary embodiment comprised of multiple straps 12, a pair of straps 12 may be oriented generally parallel to each other. In an exemplary embodiment, one or more straps 12 may be oriented generally perpendicular, or transverse to an other strap 12 or multiple other straps 12. In an exemplary embodiment, two pairs of parallel straps 12 may be generally perpendicular to each other. In the exemplary embodiment, a strap junction 34 may secure two intersecting straps 12. Such a strap junction 34 may comprise of stitching through the strap 12 material to fixedly connect a pair of straps 12.

In an exemplary embodiment, straps 12 may have a strap width W_s . In an exemplary embodiment where securing system 10 comprises a pair of straps 12 oriented perpendicular to each other, one strap 12 may have a first strap medial length S_{m1} and a second strap medial length S_{m3} , while the other strap 12 may have a first strap transverse length S_{t1} and a second strap transverse length S_{t3} . In an exemplary embodiment where securing system 10 comprises two pairs of straps 12 oriented perpendicular to each other, one pair of straps 12 may have a first strap medial length S_{m1} , an intermediate strap medial length S_{m2} , and a second strap medial length S_{m3} , while the other strap may have a first strap transverse length S_{t1} , an intermediate strap transverse length S_{t2} , and a second strap transverse length S_{t3} . A distance between any two parallel transverse straps 12 may be referred to as an intermediate strap transverse length S_{t2} . It is appreciated that an exemplary embodiment may comprise of one or more straps 12 crossing one or more other straps 12.

In an exemplary embodiment, the securing system 10 may have a strap medial length L_m and a generally perpendicular strap transverse width w_t . In an exemplary embodiment, a strap medial length L_m may be an entire length of the strap system 10, and may comprise the first strap medial length S_{m1} , a second strap medial length S_{m3} , one or more intermediate strap medial lengths S_{m2} , and as many strap widths W_s as there are straps 12 perpendicular to the strap medial length L_m . In an exemplary embodiment, a strap transverse width w_t may be an entire width of the strap system 10, and may comprise the first strap transverse width S_{t1} , a second strap transverse width S_{t3} , one or more intermediate strap transverse widths S_{t2} , and as many strap widths W_s as there are straps 12 perpendicular to the strap transverse width w_t .

Referring now primarily to FIGS. 3 through 5, details of an exemplary embodiment of an adaptable end 16 of a strap 12 is shown to comprise an anchor point 14 attached to the material of the strap 12. In the exemplary embodiment, an anchor point 14 may include a D-ring 22 attached to the strap 12 by a tab 24. The tab 24 may loop around a portion of the D-ring 22 and lay flat against itself. In this fashion, the tab 24 may be secured back upon itself to secure the D-ring 22 within the fold, and secure the tab 24 to the strap 12. Various forms of securing may be acceptable, to include stitching, rivets, or adhesives.

In an exemplary embodiment, an adaptable end 16 may include a cord cover 30 attached to the strap 12 at opposing outer edges so as to create a sleeve 32. The cord cover may be referred to as a top layer 46 and the strap may be referred to as a bottom layer 48, which together form the sleeve 32. Cord cover 30 may be made of a flexible and durable material, and in an exemplary embodiment, may be made of the same material as the strap 12. The opposing outer edges 52 of the sleeve 32 may run parallel to the length of the tension cord 18. The cord cover 30 may be formed as an integral member of one edge 52 of the strap 12. In the exemplary embodiment, one edge 52 of the cord cover 30 and strap 12 interface may be selectively securable.

Various forms of selective securing may be useable, and may include hook and loop fastener material, snaps, and a zipper, for example. In the exemplary embodiment, a hook strip 26 and a loop strip 28, of a hook and loop fastener material, are securely attached to opposing surfaces of the edges of the strap 12 and the cord cover 30, so that engaging the hook and loop fastener material secures the edges of the strap 12 and cord cover 30. So engaged, the cord cover 30 may form a sleeve 32 on the strap 12.

In the exemplary embodiment, the strap is seen, for orientation purposes, to have a middle **38**. In the exemplary embodiment, an adaptable end **16** may be seen to be located or formed at the end of the strap **12**, and thereby can be seen to have a strap end **42**, closer to the middle **38** of the strap **12**, and a terminated end **40**, closer to the end of the strap **12**. In the exemplary embodiment, an end of a sleeve **32** of an adaptable end **16** may be left open, creating an open end **44** with an opening **50**. The hook **20** distal the tab **24** may protrude from this open end **44** the end of the sleeve **32**. The sleeve **32** may protect the components of an adaptable end **16**, as well as provide a protective barrier to protect a user from various hazard, including a failure or an uncontrolled release of the tension cord **18**.

In an exemplary embodiment where a pallet **1** is about 39 inches wide and about 47 inches long, and a plurality of containers **2** each are about 15.5 inches wide by about 23.5 inches long and about 10 inches high, an appropriately sized securement system **10** may include a strap medial length L_m of about 124.5 inches and a strap transverse width w_t of about 117 inches. Such an appropriately sized securement system **10**, may have at least one adaptable end **16** that may have a length of 39 inches from the tab **14** to the end of a distal hook, with no tension on the tension cord **18**. The maximum length and tension characteristics of a chosen tension cord **18** may determine a maximum height of a supportable loaded pallet **3**, and whether that loaded pallet **3** may have four or five levels of bins **2**. A strap **12** or pair of straps **12**, in the appropriately sized securement system **10**, may include a cinching mechanism **36** to permit adjustment of the strap medial length L_m and strap transverse width w_t so as to adapt to variations in the sizes in bins **2**, pallets **1**, and loaded pallets **3**.

Referring now additionally to FIG. 6, in an exemplary embodiment, securement system **60** may comprise of multiple straps **12**, where a pair of straps **12** may be oriented generally parallel to each other. In an exemplary embodiment, straps **12** may have a strap width W_s . In an exemplary embodiment where securement system **60** may comprise a pair of straps **12** oriented parallel to each other. In an exemplary embodiment of securement system **60**, a pair of straps **12** may have a first strap medial length S_{m1} , an intermediate strap medial length S_{m2} , and a second strap medial length S_{m3} . In an exemplary embodiment, a strap transverse width w_t may be an entire width of the strap system **60**.

In an exemplary embodiment of securement system **60**, straps **12** are connected by at least one lateral support **62**, oriented generally perpendicularly to the straps **12**. In the exemplary embodiment, lateral support **62** may have a lateral support width W_l . In an exemplary embodiment, a transverse support **64** may span the distance between parallel straps **12**, generally perpendicular to straps **12**, and generally parallel to lateral supports **62**. In an exemplary embodiment, a securement system **60** may have a longitudinal support **66** connected between parallel straps **12**, and generally parallel with straps **12**, and generally perpendicular to lateral supports **62** and transverse support **64**. In the exemplary embodiment, longitudinal support **66** may not run the entire strap medial length L_m , but may end at a transverse support **64**. Lateral support **62**, transverse support **64**, and longitudinal support **66** may be constructed from similar material as the straps **12**.

In an exemplary embodiment, the securement system **60** may have a strap medial length L_m . In an exemplary embodiment, a strap medial length L_m may be an entire length of the strap system **60**, and may comprise the first

strap medial length S_{m1} , a second strap medial length S_{m3} , one or more intermediate strap medial lengths S_{m2} , and as many lateral support width W_l , as there are lateral supports **62** perpendicular to the strap medial length L_m . In each case, as described above, each strap **12** may have an adaptable end **16**.

Referring now primarily to FIGS. 7 through 12, exemplary dimensions and configurations of pallets **1**, bins **2**, and loaded pallets **3** are provided to provide visualization of at least one type of cargo with which securement system **10** may work. In the exemplary prior art illustration, securement wrap **4** is dispensed from a roll, and unrolled and stretched around the diameter of the bins **2**. Typical securement wrap **4** is made of a polymer, such as polyethylene, which adheres to itself to secure the bins **2** together, as well as securing the bins **2** to the pallet **1**.

The exemplary pallet **1** has a length L_p , a width w_p , and a height h_p . The exemplary bins **2** have a length L_b , a width w_b , and a height h_b . An exemplary loaded pallet **3** may typically be loaded to four or five layers of bins **2**, and the combined height of the containers h_c will vary accordingly. Using the exemplary bin height h_b of about 10 inches, four layers of bins **2** will result in a combined height of the containers h_c of about 40 inches. Five layers of bins **2** will result in a combined height of the containers h_c of about 50 inches.

In such an appropriately sized securement system **10**, the exemplary strap medial length L_m may include a first strap medial length S_{m1} and a second strap medial length S_{m3} , both of 53 inches, one intermediate strap medial length S_{m2} of 12.5 inches, and two strap widths W_s of three inches each. The exemplary strap transverse width w_t may include a first strap transverse width S_{t1} and a second strap transverse width S_{t3} , both of 50 inches, one intermediate strap transverse widths S_{t2} of 11 inches, and two strap widths W_s of three inches each.

These examples illustrate only a few configurations that are considered by the inventor within the scope of this disclosure. The foregoing disclosure and description of the invention are illustrative and explanatory thereof. Various changes in the details of the illustrated construction may be made, including varied combinations of the disclosed alternate embodiments, within the scope of the appended claims without departing from the spirit of the invention. The present invention should only be limited by the allowed claims and their legal equivalents.

I claim:

1. A securement system, comprising:
a strap element comprising a length of flexible, durable material, with a strap middle and a terminated end;
the strap element having an adaptable end proximate the terminated end;
the adaptable end having a strap end, a distance away from the terminated end toward the strap middle, and an open end proximate the terminated end;
the adaptable end comprising a top layer and a bottom layer, the top layer and the bottom layer forming an opening at the terminated end;
the adaptable end comprising an anchor point intermediate the top layer and the bottom layer proximate the strap end;
a net anchor attached to the strap at the anchor point; and the net anchor extendable between the top layer and the bottom layer, and through the opening.

2. The securement system of claim 1, further comprising: the top layer and the bottom layer each having an edge, which extend from the strap end to the terminated end; and the edge of the top layer releasably securable to the edge of the bottom layer.
3. The securement system of claim 1, further comprising: the top layer and the bottom layer each having a first edge and a second edge, which extend from the strap end to the terminated end; the first edge of the top layer securely attached to the first edge of the bottom layer; and the second edge of the top layer releasably securable to the second edge of the bottom layer.
4. The securement system of claim 1, further comprising: the net anchor comprising an elastic cord having a first hook and a second hook; the first hook attachable to the anchor point; and the second hook extendable through the opening.
5. The securement system of claim 1, further comprising: the top layer and the bottom layer each having an edge, which extend from the strap end to the terminated end; the edge of the top layer releasably securable to the edge of the bottom layer; the net anchor comprising an elastic cord having a first hook and a second hook; the first hook attachable to the anchor point; and the second hook extendable through the opening.
6. The securement system of claim 1, further comprising: the top layer and the bottom layer each having a first edge and a second edge, which extend from the strap end to the terminated end; the first edge of the top layer securely attached to the first edge of the bottom layer; the second edge of the top layer releasably securable to the second edge of the bottom layer; the net anchor comprising an elastic cord having a first hook and a second hook; the first hook attachable to the anchor point; and the second hook extendable through the opening.
7. The securement system of claim 1, wherein the anchor point is a D-ring.
8. A securement system, comprising:
a strap element comprising a length of flexible, durable material;
one end of the strap element having an anchor point a distance from the end of the strap element, and a cord cover extending from the anchor point to the end of the strap element; and

- a sleeve removably attached to the strap element at one edge to provide an interior extending from the anchor point to the end of the cord cover and open at the end distal the anchor point.
9. The securement system of claim 8, wherein the anchor point comprises a removable connection to an end of a tension cord.
10. The securement system of claim 9, wherein the tension cord having a second end extendable from the end of the sleeve, and the second end comprises a removable connection to a cargo pallet.
11. The securement system of claim 8, wherein the anchor point is a D-ring.
12. The securement system of claim 11, wherein a hook and loop fastener strip forms the removable attachment of the sleeve to the strap at one edge.
13. A securement system, comprising:
at least four straps, each strap having an anchor point and an end;
at least one strap having the anchor point within an openable protective sleeve attached to the strap;
a first pair of straps, parallel to each other and spaced apart a first distance;
a second pair of straps, perpendicular to the first pair of straps and spaced apart a second distance;
the first pair of straps having a first pair anchor point on each strap a third distance from at least one end of the first pair of straps; and
the second pair of straps having a second pair anchor point on each strap a fourth distance from at least one end of the second pair of straps.
14. The cargo securement system of claim 13, further comprising:
the openable protective sleeve comprising one edge removably attachable to an edge of the strap creating an interior extending from the anchor point to the end of the strap; and
an opening in the interior at the end of the strap.
15. The cargo securement system of claim 13, wherein the first distance is not equal to the second distance.
16. The cargo securement system of claim 13, wherein the first distance is 11 inches.
17. The cargo securement system of claim 13, wherein the first distance is 12.5 inches.
18. The cargo securement system of claim 13, wherein the third and fourth distances are equal.
19. The cargo securement system of claim 13, wherein the third and fourth distances are equal to or less than 39 inches.
